(57) **CLAIM**

The ornamental design for a Y-connector for a stereo headset, as shown and described.

DESCRIPTION

FIG. 1 is a rear elevated view of a Y-connector for a stereo headset;

FIG. 2 is an enlarged rear view of the Y-connector;

FIG. 3 is an enlarged side view of the Y-connector, the opposite side is a mirror image; and,

FIG. 4 is an enlarged front view of the Y-connector.

The broken lines are included for the purpose of illustration and form no part of the claimed design.
